CLAIM

The ornamental design for a fishing cart, as shown and described.

DESCRIPTION

FIG. 1 is a top, front perspective view of a fishing cart, showing my new design;

FIG. 2 is a bottom, rear perspective view thereof;

FIG. 3 is a front elevational view thereof;

FIG. 4 is a rear devotional view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated in FIG. 1; and,

FIG. 10 is an enlarged view of a portion indicated in FIG. 2. The broken lines in FIGS. 1, 2, 9 and 10 are for the purpose of depicting the cut line of the enlarged view and that form no part of the claimed design.
